UNITED STATES PATENT OFFICE

MARSHALL E. CRUME, OF PERU, INDIANA, ASSIGNOR TO MIAMI MANUFACTURING COMPANY, OF PERU, INDIANA, A CORPORATION OF INDIANA

DOOR

Application filed June 24, 1931. Serial No. 546,653.

This invention relates to vertically folding doors suitable for use in garages, warehouses and like structures.

An object of the invention is to provide a door composed of a plurality of sections adapted to be folded upwardly against the door frame and of such structure, improvements and arrangement of parts that a well balanced and easily operated door results.

Another object is to provide a door which in itself is a complete unit and one that due to its structure is absolutely sagless since the counterweight carries the weight of the sections in all positions without any strain on the hinges and one in which installation is comparatively simple.

A further object of this invention is to provide a door in which the carrier plates are so designed and mounted that the bottom section is prevented from rattling or moving back and forth after the door has been closed.

Referring to the accompanying drawings, which are made a part hereof and on which similar reference characters indicate similar parts,

Figure 1 is a view in elevation of the inside of the door in closed position with portions broken away to show details,

Figure 2, a view in elevation of a portion of the door in closed position showing a detail of the upper and lower carrier plates, guide elements, rubber bumper, hinge, a section of the cable and the closing plate,

Figure 3, a perspective view of the portion shown in Figure 2, but in partial opened position,

Figure 4, a section on line 4-4 of Figure 2 showing the details of the carrier plates,

Figure 5, a vertical section of the operating handles and lock, and

Figure 6, a section on line 6-6 of Figure 5, showing the detail mechanism of the operating handles and lock.

In the drawings numerals 10 and 11 indicate the sides of the door frame connected at their tops by a horizontal beam 12 on which the door sections are hinged. The upper section 13 is secured to the underside of the horizontal beam by means of hinges

14. The intermediate or middle section 15 is secured to section 13 by hinges 16 on the outside face of the door. The bottom section 17 is secured to the middle section by hinges 17' on the inside of the door. An interchangeable hollow upright column 11' may be secured to one side or the other for housing the counterbalancing mechanism and its location depends on the particular installation.

The sides 10 and 11 are provided with flat plates 18 and 19 secured by any suitable means to their edges and which serve as guide channels for the folding sections of the door. The outer plates 19 are of a width substantially greater than the inside plates 18 and extend well over the edges of the sections and insure a tight fit even if there are slight variations in setting the door in place.

Opposite the lower hinges 17' the sides of the sections 15 and 17 are provided with cut-out portions. Carrier plates 20 and 21 are secured flush with the edges of the sections and are provided with a flange 20' and 21' respectively embedded in the inner face of the respective sections. The inner ends of the carrier plates project over the cut-out portion and are provided with inwardly extending spring-pressed pins 22 and 23 in contact with the face of the cut-out portions of the sections. Opposite the pin 23 on the middle section and projecting outwardly, a stub shaft 26 having a ball-bearing roller 27 is mounted and is further provided with a slot 28 with rounded edges.

The pin 22 and the stub shaft 24 on the bottom section are slightly displaced inwardly with respect to the center line of the shaft 26 for a purpose which will later appear. The shaft 24 also has a ball-bearing roller 25 mounted on its end and is further provided with a collar 29 on its body for attaching a cable thereto.

A single pulley 30 is secured at one end of the horizontal beam 12 and a like pulley 31 at the other end. A larger pulley 32 is secured adjacent the end of the pulley 31 but slightly displaced therefrom.

Cables 33 and 34 are connected to the col-

lars 29 on the stub shafts 24, extending upwardly through the slots 28 over the pulleys 30 and 31 respectively. The edges of the slots 28 are rounded in order to permit free movement of the cables and prevent binding regardless of the position of the door sections in order to insure a free operating action. The cable 33 extends along the horizontal beam 12 and over pulley 32. The free ends of the cables are secured to an equalizing bar 35 which is pivoted at its center to an operating handle 36 and a series of plates 37. The plates serve as a counterbalance for the door and are housed in the column 11'. The plates 37 may be varied in number according to the weight necessary for the counterbalance which depends on the weight of the door. The outer plates are provided with rollers 38 to insure free movement and prevent binding of the counterbalance in its travel. A slot 39 is provided in the column 11' from which the handle 36 projects and slides as the door is operated.

In order to completely seal the door from outside elements and for the neat appearance of the door, angle closing plates 40 are provided. These plates consist of two flanges at right angles to each other. The upper portion of the flange parallel to the door facing is provided with a slot 41 adapted to be secured beneath the spring-pressed pin 23. The other pin 22 is adapted to frictionally engage this flange at its other end. The other flange completely covers the cut-out portions and rests against the channel plates 19 and slides under the pin 23 as the door is operated.

The door may be locked by mechanism mounted to be operable from either side comprising a casing 42 provided with a rotatable disk 43 mounted in its face having a hand grip 44 secured to the outside thereof and an inwardly projecting plate 45 on the other side and of sufficient length to be engaged by a similar hand grip 58 on the other side of the door. A pair of operating plates 46 is mounted in the casing and is provided with tabs 47 which project from the sides of the casing through suitable openings. The plates 46 are further provided with flanges 48 resting on each side of the plate 45. A rod 49 projects through the flanges 48 and the plate 45 and is keyed at 50 to each side of the casing. Springs 51 are mounted between the flanges 48 and the sides of the casing for holding the flanges 48 against the projecting plates 45.

Attached to the tabs 47 are rods 52 which extend to the spring-pressed plunger latches 53 and are properly tensioned by the couplings 54. A lock 55 is secured to the lower side of the casing 42 and is provided with a plunger 56 which engages the slots 57 in the operating plates 46 to lock them in fixed

position. It will be noted that by turning the handle either to the right or left the rods will be actuated.

The plungers 53 engage suitable catches 59 mounted on the sides of the door for holding the sections in place. Small rubber bumpers 60 may be secured on the sections to prevent injury to the sections or the locking mechanism as the door sections are folded together. 75

The operation of the door is as follows:

Considering the door is in closed position as shown in Figure 1, by simply grasping the handle on either side and turning it in either direction, the plungers 53 are released from the catches 59 and by slight pull on the handle the door sections will break and being of such construction and so well balanced the door is easily raised to open or folded position with little effort on the part of the operator. 80 85

It will be noted that the handle 36 on the counterbalance is now in lowered position. To close the door the operator simply raises this handle and the sections unfold. As the bottom section nears its final position, the rollers on the stub shafts 24 tend to press against the inner plates 18 of the channel guides and the rollers 27 against the plate 19 of the channel guide thereby binding the bottom section in fixed position which prevents swinging or rattling of this section, as is usually the case in doors of other constructions. This particular feature is accomplished by having the lower shaft 24 slightly displaced inwardly with respect to the line of center of shaft 26. As the door reaches its final position the latches snap into position. 90 95 100

In closing or opening the door the closing plates 40 slide along the outer channel plates 19 and are held in position by the action of the spring pressed pins in their travel. 105

From the foregoing it will be seen that my door is simple in structure, easily assembled and with parts interchangeable to suit particular installations and a door that requires scarcely any effort on the part of the operator and above all a well constructed door suitable for varied purposes and with special features not found in doors as heretofore constructed. 110 115

It may be observed that with two cables there is also little or no danger of injury should one cable break since the other cable is of sufficient strength to hold the sections in any position. 120

It will be obvious to those skilled in the art that various changes may be made in my device without departing from the spirit of the invention and therefore I do not limit myself to what is shown in the drawings and described in the specification, but only as indicated by the appended claims. 125 130

Having thus fully described my said invention, what I claim as new and desire to secure by Letters Patent, is:—

1. The combination with a folding door formed of a plurality of sections hinged together, of plates forming guide channels mounted on each side of the door, the outer plate being of a width sufficient to extend over the edge of the sections to form a tight fit, guide elements mounted on the edges of the bottom and intermediate sections on each side of the hinged joint and extending into said channels, the guide element on the bottom section being displaced inwardly with respect to the guide element on the intermediate section and adapted to press against the inner plate when the door is in closed position thereby preventing swinging of the bottom section of said door, substantially as set forth.
2. In a folding door comprising a frame, a plurality of sections hinged together, the upper section being hinged to the top of said frame and the lower sections being provided with cut-out portions on the edge adjacent the hinged joint, plates secured to the edges of said sections provided with inwardly projecting pins and outwardly projecting guide elements, said pins resiliently engaging said cut-out portions and an angled plate having one flange extending over the opening formed by the cut-out portions for closing the same mounted beneath said pins, substantially as set forth.
3. In a folding door comprising a frame, a plurality of sections hinged together, the upper section being hinged to the top of said frame, the bottom and intermediate sections provided with cut-out portions on the edges thereof adjacent the hinged connection, plates secured to the edges of said sections provided with outwardly projecting guides and inwardly projecting pins, angled plates pivotally secured at one end by the pins on the intermediate sections and slidably secured under the pins on the bottom section for covering the opening formed by the cut-out edges and a system of weighted cables and pulleys for counterbalancing said door fixed to said guides, substantially as set forth.

In witness whereof, I have hereunto set my hand and seal at Washington, D. C., this 17th day of June, A. D. nineteen hundred and thirty-one.

MARSHALL E. CRUME.
